Specification for Design.

Patented July 25, 1922.

Application filed June 7, 1921. Serial No. 475,733. Term of patent 14 years.

To all whom it may concern:

Be it known that we, CLARENCE V. ROBERTS and KENNETH C. FARNSWORTH, citizens of the United States, residing in Philadelphia, Pennsylvania, have invented a new, original, and ornamental Design for a Gas Heater, of which the following is a specification, reference being had to the accompanying drawings, forming part thereof, in which—

Fig. 1 is a perspective view of a gas heater illustrating our new design;

Fig. 2 is a detached plan view of the front plate showing the shape and configuration of the top surface thereof; and

Fig. 3 is a sectional view on the line 3—3, Fig. 2, showing the curve of the front plate.

We claim:

The ornamental design for a gas heater, substantially as shown.

CLARENCE V. ROBERTS.
KENNETH C. FARNSWORTH.
